UNITED STATES PATENT OFFICE.

HAROLD G. BAXTER, OF BALDWIN, NEW YORK, ASSIGNOR TO WESTINGHOUSE ELECTRIC & MANUFACTURING COMPANY, A CORPORATION OF PENNSYLVANIA.

SAFETY-SWITCH BOX.

Application filed November 20, 1920. Serial No. 425,479.

To all whom it may concern:

Be it known that I, HAROLD G. BAXTER, a subject of the King of Great Britain, and a resident of Baldwin, Long Island, in the 5 county of Nassau and State of New York, have invented a new and useful Improvement in Safety-Switch Boxes, of which the following is a specification.

My invention relates to switch mechanism 10 and particularly to safety switches used in controlling electrical circuits of lighting and power systems such as are installed in residences and factories.

One object of my invention is to provide 15 an extremely simple safety switch mechanism wherein a minimum number of parts are necessitated for so interlocking the housing cover with the switch that the cover cannot be opened so long as the switch is in closed position and the switch cannot be 20 closed so long as the cover is in open position.

Another object of my invention is to provide a simple mechanism having the above 25 characteristics that may be formed from sheet metal by simple and inexpensive stamping operations.

A further object of my invention is to provide a single switch organization that 30 may be readily assembled and inspected.

These and other objects, that will be made apparent throughout the further description of the invention, are attained by means of a mechanism hereinafter described and illustrated in the accompanying drawings, 35 wherein:

Figure 1 is a longitudinal section through the housing, showing the switch mechanism in side elevation.

Fig. 2 is a transverse section taken 40 through the housing in the line II-II of Fig. 1, showing the fuse and switch mechanism in end elevation.

Referring to the drawings, the apparatus 45 includes a housing 3 having a stationary cover portion 4 and a movable portion or door 5 that is hinged, as at 6, to the stationary cover portion.

The switch mechanism is mounted upon 50 an insulating base 7 that is secured to the bottom of the housing and supports the fuse receptacles 8, the pivot jaw members 9 and the contact jaw members 10. The switch blade members 11 are pivoted to the 55 switch jaw members 9 and are movable into

and out of engagement with the contact jaw members 10.

The live conductors 12 are secured to the terminal members 13, and current passes first through the switch blade 11 to the fuse 60 clips 8 through connectors 14 which conductively connect the fuse clips 8 to the pivot jaw members 9. The load terminals 14 are connected to the terminal members 15 that are conductively joined to the fuse clips 8. 65 Detachable fuses 16 are adapted to be inserted into the clips and are accessible through the opening that is normally closed by the door or cover 5.

The switch blade members 11 are connected at their free ends by means of an insulating bar 17 and are operated by a pull rod 18 that is pivoted, at its inner end, to the insulating bar 17 by means of a pivot pin 19. The outer end of the operating handle 70 or pull rod is provided with an enlarged end portion 21 having a perforation 22 through which a finger or a "hook stick" may be inserted for the purpose of manipulating the pull rod.

The pull rod projects from the stationary cover through an opening 23 provided therein and is retained in closed position by means of a latch extension 24 that is so disposed adjacent the enlarged end of the handle that it will engage the end of the slot 23 and prevent outward movement of the pull rod.

When the box is in operative position on a wall, it is so disposed that the opening 5 90 in the housing is at the lower end of the box and, consequently, the handle or pull rod 18 normally occupies the position illustrated, by reason of the force of gravity.

The cover or door 5 is provided, on its 95 underside, with a bracket 26 having an arcuate slot 27 disposed concentric to the hinge 6. A link 28 is pivoted, at one end, as at 29, to the pull rod 18 and, at the other end, it is provided with a pin 31 that extends through the slot 27 and operates therein.

The link 28 provides a lost-motion connection between the cover 5 and the pull 100 rod 18, and when the switch and cover are in the closed positions illustrated in full lines in Fig. 1, the pull rod may be released by moving it in a clockwise direction until the projection 24 clears the end of the slot 23, at which time the pull rod may be pulled 105 110

outwardly to open the switch. During this operation, the pin 31 is free to move in the slot 27, and the switch may, therefore, be operated independently of the door.

- 5 However, it will be apparent that the cover or door 5 cannot be opened, so long as the switch is in closed position, by reason of the link 28 which prevents displacement of the cover so long as the latch 24 remains 10 in engagement with the slot 23. After the switch has been opened to the position shown in broken lines in Fig. 1, the door may be moved to the open position illustrated in broken lines in the same figure. 15 When the door 5 is in the open position illustrated, the pull rod cannot be moved to closed position without first moving the cover to closed position.

It will be seen from the foregoing that 20 access may not be had to the fuse compartment for the purpose of inspection or renewal of the fuses without first opening the switch, which operation disconnects the live conductors 12 from the fuse clips. It will 25 be further apparent that the switch cannot be closed without first closing the door 5.

The switch mechanism is safe in every respect, and the parts are simple and inexpensive to manufacture and may be readily 30 assembled or inspected.

While I have described and illustrated but one embodiment of my invention, it will be apparent to those skilled in the art that various changes, modifications, substitutions, 35 additions and omissions may be made in the apparatus illustrated without departing from the spirit and scope of the invention, as set forth in the appended claims.

I claim as my invention:

- 40 1. Switch mechanism comprising a housing, a stationary cover portion, a movable cover portion, a switch member, a handle for the switch operating through an opening in the stationary cover portion, a lost-motion connection between the movable cover and the handle for preventing opening movement of the said cover independently 45 of the switch when the switch is in closed

position, and means on the handle to co-operate with the stationary cover for normally preventing opening movement of the switch. 50

2. Switch mechanism comprising a housing, a movable cover for the housing, a switch member, a pull rod for the switch member, a link pivoted to the pull rod and having a lost-motion connection to the cover for preventing opening movement of the cover independently of the switch when the switch is in closed position, and means 55 on the pull rod and engaging the housing for normally preventing opening movement of the pull rod. 60

3. Switch mechanism comprising a housing, a movable cover for the housing, a switch member, a pull rod for the switch member extending exteriorly of the housing, a lost-motion connection between the cover and the pull rod for preventing opening 65 movement of the cover independently of the switch when the switch is closed and closing movement of the switch independently of the cover when the cover is open, and means on the pull rod for engaging the housing for preventing opening movement of the pull rod. 70

4. Switch mechanism comprising a housing, a stationary cover portion, a movable cover portion, a switch member, a pull rod for the switch operating through an opening in the stationary cover portion, a slotted member carried by the movable cover extending into the housing, a link pivoted to the pull rod and slidably engaging the slotted member for substantially preventing 75 opening movement of the movable cover independently of the switch when the switch is in closed position, and a latch member engaging the stationary cover portion for normally preventing opening movement of the pull rod by the cover. 80

In testimony whereof, I have hereunto subscribed my name this third day of November 1920.

HAROLD G. BAXTER.
